James Wager, Volney Richmond, and
Harvey Smith, of Troy, N.Y.
Letters Patent No. 683. Dated Jan. 22, 1855.

The schedule referred to in these Letters Patent, and making part of the same.

To all whom it may concern:

Be it known, that we James Wager, Volney Richmond, and Harvey Smith, of Troy, in the County of Rensselaer, and State of New York, have invented or produced, a new and original design of Parlor-Stove plates, which we call the "Triumph," and we do hereby declare that the following is a full, clear, and exact description of the same, reference being had to the annexed drawings, and letters of reference marked thereon making part of this specification, in which

Fig: 1. is a perspective view of the stove.

Fig: 2. is a view of the ornamental top plate.

Fig: 3. is a view of the back plate.

Our design of stove plates consists of the bottom plate A. (fig:1.) with the ornamental bordering (a a); the front plate B. ornamented with the buttresses (b. b.) and moulding (c) at top. C. is a drop door, ornamented with a shell (d) D. is a damper, ornamented with shell work (e). E. is the end plate with the ornamental panel (f), and ornament (g) on the face of the plate. F. is the top plate, having the ornamental border (h). G. (fig:2) is the ornamental false top plate, the design of which is composed of the leaves (i), arranged in the center, and at each end, the scrolls (j, j) shells (k, k) and (l, l), the whole surrounded by the moulding (m). H. (fig:3) is the back plate, ornamented on the face with the moulding (n).—

Having described our design for parlor-stove plates, what we claim as new, and desire to secure by Letters Patent, is the ornamental design and configuration of parlor-stove plates, such as herein described, and shown in the annexed drawings.—
